UNITED STATES PATENT OFFICE

AUGUST C. BRILL, OF OBERURSEL, NEAR FRANKFORT-ON-THE-MAIN, GERMANY, AS-
SIGNOR TO THE TURNER TANNING MACHINERY COMPANY, OF PORTLAND, MAINE,
A CORPORATION OF MAINE

PLATING SKINS

Application filed June 8, 1926, Serial No. 114,491, and in Germany August 1, 1925.

This invention relates to apparatus and methods for treating skins and is herein exemplified in its application to what is commonly termed the plating of skins, that is, to the smoothing or ironing of skins by pressure-applying plates or platens.

The plating of skins has heretofore been commonly performed by the use of presses comprising upper and lower presser members relatively movable toward and from each other and of such surface dimensions as to be large enough to press at one operation skins of considerable size, such as calf skins. Commonly, skins are considerably wrinkled or creased at or adjacent to their edge portions, particularly along the shank and flank portions of the skins. In the use of presses of the type referred to, difficulty has been experienced in eliminating such creases and wrinkles and in preventing the formation of other creases, wrinkles, folds or tucks. It will be readily understood that such creases, wrinkles, folds, or tucks in portions of a plated skin are firmly set in the skin and that, as a consequence, the value of such portions is greatly reduced, if not altogether destroyed. In plating operations as heretofore conducted the operator attempts to smooth out with his hands the folded or wrinkled portions around the edges of the skin before the plating action of the presser members. While he is fairly successful in this operation there are many instances in which the fold or wrinkle refuses to stay smoothed-out sufficiently to prevent a partial wrinkle or fold appearing in the plated skin. A great deal depends on the skill and care of the operator, since the creases, wrinkles, folds or tucks cannot be held in smoothed-out condition after the machine starts in operation. Furthermore, it has occasionally happened that injury has resulted to the operator in attempting, at the last second as the presser members are approaching each other, to smooth out a fold or wrinkle which has proved refractory to manipulation.

In view of the foregoing, it is an object of this invention to provide for the plating of skins, and particularly of small skins such as sheep, kid and goat skins wherein the occur-

rence of wrinkles and folds in the edge portions thereof is common, so as to minimize the formation of wrinkles and folds in the plated skins, and at the same time practically eliminate danger of injury to the operator.

55

To this end and in accordance with important features of the invention, there is provided a press adapted for plating skins and having relatively movable presser members, the transverse dimensions of one or both of the presser members being considerably less than the diametric dimensions of the skins to be operated upon, the plating members being adapted to perform plating operations step by step upon successive portions of a skin. In the use of such a press, a skin may safely and conveniently be held by the hands of the operator at each side of and beyond the edges of the presser member or members in such manner as to smooth out existing creases or wrinkles and to prevent the occurrence of other creases, wrinkles, tucks or folds in the plated skin. In the illustrated construction, the presser members are substantially triangular in shape, the widest part of each presser member being substantially shorter than its greatest lengthwise dimension. That the generally triangular shape of the illustrated presser members is itself of considerable importance will be readily appreciated when it is understood that in performing plating operations step by step around the periphery of a skin, in each such operation the peripheral portion of the skin to be plated is of considerably greater extent than the portion to be treated in the central part of the skin. In the use of the illustrated construction, while the smaller end portions of the presser members are operating on the central portions of the skin, the wider base portions of the triangularly shaped pressers plate the larger peripheral areas of the skin in the same number of pressing operations.

60

Further to facilitate the prevention of folds or wrinkles, the co-operating presser members may advantageously have portions of their operating surfaces curved in directions extending transversely of the presser members beginning at a substantial distance

80

85

90

95

100

back from the front ends of the presser members, one presser surface being concave and the other correspondingly convexly curved. As shown, the work supporting 5 presser member presents, to the rear of a flat pressure surface, a concave pressure surface and the upper presser member a correspondingly curved convex surface back of a flat pressure surface at the front end of the 10 presser member. This construction takes advantage of the fact that the central portion of a skin is normally practically flat, while the peripheral portions are normally somewhat rounded in contour. Thus the co-operation 15 of the convex and concave surfaces of the presser members is particularly efficient in eliminating wrinkles or folds in the edge portions of the skin, without danger of producing other folds or wrinkles, while the flat 20 portions of the presser members are adequate to plate the substantially flat central portions of the skin.

Moreover, since the illustrated presser members are of relatively small dimensions 25 as compared with the presser members of prior constructions the work may be more quickly introduced and hence the machine may be operated more rapidly than was possible before, so that even with the necessary 30 repetition of operations upon a single skin to effect proper plating thereof the time involved is more than offset by the improved results obtained.

In its method aspect, the present invention resides in plating skins by alternately 35 repeated operations, which comprise tensioning of edge portions of a skin to efface wrinkles, tucks, or other folded portions, and while maintaining the tension subjecting the tensioned portions to a smoothing 40 operation.

Other features of the invention and novel 45 combinations of parts will be described in detail in the specification and pointed out in the appended claims.

In the drawings,

Figure 1 is a view in side elevation of a 50 press showing one embodiment of the invention;

Fig. 2 is a plan view from above of the triangular presser members employed in the machine shown in Fig. 1, illustrating the manner of operating on the work;

Fig. 3 is a similar view with the work at 55 a different position from that shown in Fig. 2;

Fig. 4 is a transverse section along the line IV—IV of Fig. 5 looking in the direction of the arrows; and

Fig. 5 is a view in side elevation of the 60 presser members shown in section in Fig. 4.

Referring to Fig. 1 of the drawings it will be observed that the press therein shown and designed for plating skins comprises an upper presser member 10 and a lower presser

member 12, the latter serving as a work support. For supporting the upper presser member 10 there is provided a lever 14 pivoted at 16 and arranged to be operated by a toggle 17. Upon straightening the toggle 70 17 the presser member 10 is moved to operative position, that is, toward the work on the presser member 12, the movement being such that at the termination thereof the pressure surface of presser 10 is substantially in a horizontal plane. The lower presser member or work support 12 is carried by a piston 18 movable vertically within a cylinder 20 through power applied by hydraulic means including a pipe 22. When the upper presser 75 10 has been moved to operative position, the piston 18 is operated in properly timed relation to lift the lower presser or work support 12 into pressing relation with respect to the presser 10. The upper presser member 10 is heated by means of steam supplied from any convenient source by means of a pipe 24. For a more complete disclosure of parts of the press shown in Fig. 1 and not fully shown and described herein reference should be had to Letters Patent No. 981,468 granted Jan. 10, 1911, upon application of F. J. Perkins. It is to be understood that while the invention is exemplified as embodied in a press of the type disclosed in these Letters Patent and in its application to the plating of skins, this is for purposes of illustration only, since the invention is not limited to embodiment in presses of this type or to use in plating skins.

The illustrated presser members 10 and 12 have relatively small surface areas, being, as shown in Figs. 2 and 3, considerably smaller in all their transverse dimensions than the diametric dimensions of even such small skins as kid and goat skins. The purpose of having the presser members so narrow in their transverse dimensions is to provide for engagement of only a portion of the work during each pressing or plating operation so that the hands of the operator may be engaged with the work on each side of the presser members to keep the work and particularly the edges of the work smoothed out whereby any crease, wrinkle, fold or tuck is effaced prior to the pressing or plating operation without danger of forming other plates or wrinkles. It is preferable to begin the work of plating by introducing the butt end of the skin and then shifting to one flank portion or the other as may be most convenient for the operator and thus progressively plating the skin step by step until the circuit of the peripheral portions of the skin has been made. It will be observed that in Fig. 2 a skin 30 has been operated upon to such an extent as to remove all of the creases, wrinkles, folds or tucks from the butt portion 32 and that a flank portion 34 of the skin is undergoing a plating operation between the presser members 10 and 12 while the head and neck por-

tions 36 and the other flank portion 38 are still unoperated upon as evidenced by the wrinkles and folds illustrated at 40.

Fig. 3 shows a pressing operation upon a similar skin 31 in which a portion of the butt 32 and a portion of the flank 34 is undergoing a presser or plating operation. Ordinarily about eight operations of the press are necessary in securing the plating of an entire skin. However, because of the facility with which the work may be presented to the press and also because of the size of the press itself, the operations may be repeated with considerably greater rapidity than would be the case 10 with larger presses and larger work. The high quality of the work more than makes up for any difference in quantity produced with the employment of prior constructions with which the plating was accomplished in one or 15 two steps. It will be observed that the presser members 10 and 12 are roughly triangular in shape in plan view with the front end 50 of each presser member somewhat rounded and with all of the transverse dimensions of the 20 presser members (including the median transverse dimension 51) considerably shorter than the median longitudinal dimension thereof. It is clear that the herein disclosed method of operating to plate a skin, involving as it does a step by step plating operation 25 around the periphery of the skin where the wrinkles, folds or tucks occur, provides or calls for a greater plating area around the peripheral portions of the skin than in the 30 central portions thereof. Hence while the smaller end portion 50 is operating upon the middle or central portions of the skin, the wider portions of the triangular presser members take care of the larger areas of the 35 peripheral portions in the same number of 40 pressing operations. In operating the machine it will be understood that in each succeeding plating or pressing operation a portion previously pressed or plated is over- 45 lapped to insure that no line of demarcation will appear to mar the surface of the finished work. In most classes of work the skin will be presented with the grain side up to receive directly the plating action of the heated 50 presser 10.

When it is recalled that skins, when in the form of leather, retain much of the curved contour of the body of the animal from which the skin was obtained, it will be readily 55 understood that the middle or central portions of a skin are apt to be fairly flat while the flank portions and even portions of the head and neck are naturally curved in contour, so that when a skin is placed upon a flat 60 surface the middle portions along the backbone line will lie flat upon the surface while the flank or skirt portions will not lie flat. Upon any attempt to flatten out these flank portions, folds and wrinkles will appear which ordinarily may be chased from 65

one portion to another of the peripheral part of the skin. It is the presence of these wrinkles, folds and tucks that make it so difficult to plate an entire skin at one operation, and this is particularly true with kid 70 and goat skins. As a matter of fact there was always some crease or fold or tuck which did not flatten out when the presser members were operated in the machines of prior constructions, with the result that a 75 tuck or fold was set permanently in the plated marginal portion of the skin, thus reducing the value of the skin very materially especially if there were many such plated creases or folds in a given skin. With the triangularly 80 shaped presser members disclosed in Figs. 2 and 3, it is possible for the operator to hold each successive edge portion in extended condition, thus eliminating wrinkles, folds or tucks before and during a pressing and plating operation.

A modified construction of presser members is shown at 60, 62 in Figs. 4 and 5, and is based upon the fact that the central portion of a skin is practically flat while the peripheral portions are made up of portions rounded in contour, as already described. In other words, the flank or skirt portions are fuller, that is, of greater extent, than the central longitudinal portion with which they are 90 integral. Since the middle portion of the skin is flat, flat surfaces 64, 66 (Fig. 5) are retained in the front end portions 70 of the presser members 60, 62; the end portion 70 of the presser members 60, 62 corresponding to the end portion 50 of the presser members 10 and 12. For contacting with and operating upon the flank or skirt portions of the skin there is provided on the upper presser member 60, merging into the flat surface 64, a 100 curved surface 72 which is convex and adapted to fit into a complementally curved concave surface at 74 which merges into the flat surface 66 in the lower presser member or work support 62. This concave surface 74 on the presser 62 is formed in part by extensions or flanges 75 integral with the presser. It is to be understood that the presser members 60 and 62 are triangular in shape in plan view as are the presser members 10 and 12. Because of the shape of the co-operating surfaces 72, 74 the fuller flank portions 34, 38 of a hide 30 are operated upon most effectively at the same time that the flat portion in the middle part of the skin is operated upon by the flat portions 64, 66 at the forward ends 70 of the same presser members. Conveniently, the upper presser member is heated by means of steam passed through passages 80 in the body of the presser member.

In the operation of the machine a skin, such as that shown at 30, is placed, preferably with the grain side up, upon the lower presser member 12 or 62 as the case may be, preferably with the butt portion of the skin in posi- 120 125 130

tion for the first pressing operation, the hands of the operator being engaged in holding the skin with the peripheral portions thereof in extended condition to eliminate the wrinkles or other folded portions. After each pressing or plating operation the skin is shifted to operate on a portion next adjacent to the freshly plated portion, and this is repeated until all of the skin has been operated upon.

Having thus described my invention, what I claim as new and desire to secure by Letters Patent is:—

1. In a press for treating small skins, a work supporting member and a co-operating presser member having parallel surfaces when in operative position and relatively movable in a direction toward and from each other in straight-line reciprocation during pressing operations, said presser member having a pressure surface the greatest transverse dimension of which is considerably less than the diametric dimensions of kid skins to permit the operator to grasp a skin upon each side of the presser member to exert tension thereon during a pressing operation.

2. In a press for plating small skins, a pair of triangularly shaped presser members having coextensive pressure surfaces for engaging opposite sides of a skin to plate the same, the median transverse dimension of one of the presser members being considerably less than the diametric dimensions of the kid skins to permit the operator to grasp a skin upon each side of the presser members to exert tension thereon during a pressing operation.

3. In a press for plating hides, skins, and pieces of leather, a pair of triangularly shaped presser members having coextensive pressure surfaces for engaging opposite sides of a piece of work to press the same, the greatest transverse dimension of the pressure applying surface of each presser member being considerably less than the longitudinal dimension thereof, and means for relatively operating the presser members.

4. In a press for plating skins, a pair of presser members having respectively a concave and a complementally curved convex surface for accommodation of curved body portions of a skin and for co-operation with each other in pressing a skin to obtain a smooth surface, and means for causing relative straight line reciprocation of the presser members in a direction from and toward each other to effect a plating of the skin.

5. In a press for plating skins, a pair of presser members having respectively a concave and a complementally curved convex surface for accommodation of curved body portions of a skin and for co-operation with each other in pressing a piece of work, the concave and the convex pressure applying surfaces being each triangular in shape.

6. In a press for pressing work such as

leather, a triangularly shaped work support having a concave surface, and a triangularly shaped presser for co-operation with the work support in a pressing operation, the presser having a convex surface substantially complementary to the concave surface of the work support.

7. A press for plating small skins through successive operations on marginal portions thereof comprising presser members provided with triangularly shaped pressure applying surfaces each having a maximum transverse dimension substantially less than the longitudinal dimension thereof, the presser members having complementally curved co-operating concave and convex surfaces for operating on successive portions of the skin.

8. In a press for plating skins or leather, a support having a concave pressing surface, said support having extensions for increasing the size of the concave pressing surface to accommodate the full skirt portions of the skin being operated upon, and a presser having a convex surface curved complementally to the concave surface of the support.

9. In a press for treating skins or leather, a work support having a concave surface, a presser having a correspondingly curved convex surface for co-operation with the concave surface of the support, the front end portions of both work support and presser having flat co-operating pressure surfaces.

10. In a press for pressing work such as skins or leather, a work support having a flat and a concave surface, and a presser for co-operation with the work support in a pressing operation, the presser having a flat surface and also a convex surface substantially complemental to the concave surface of the work support, whereby the flat and curved surfaces substantially conform to the various surface contours of the leather.

11. In a press for plating leather, a work support having a concave surface, a presser having a complementally curved convex surface for co-operation with the concave surface of the support, said work support and presser being triangular in shape with apical ends projecting toward the front of the press, and having co-operating flat surfaces at their front apical ends, and means for relatively operating the work support and the presser.

12. In a press for plating skins, a support having a concave surface, a presser having a convex surface curved complementally to the concave surface of the support, said surfaces being constructed and arranged to accommodate the full skirt portions of a skin, and means for heating the presser.

13. That improvement in methods of plating skins which comprises tensioning edge portions of a skin to efface wrinkles, tucks or other folded portions, and while maintaining the tension subjecting the tensioned portions of the skin to a pressing operation.

14. That improvement in methods of plating skins which comprises, tensioning edge portions of a skin to efface wrinkles, tucks or other folded portions, subjecting the tensioned edge portions of the skin to a smoothing operation while maintaining the tension thereon, and simultaneously therewith smoothing central portions of the skin which are normally flat and free from wrinkles, folds or tucks. 70
15. That improvement in methods of plating skins which comprises, tensioning edge portions of the skin to efface wrinkles, tucks or other folded portions, subjecting the tensioned edge portions to a smoothing operation while maintaining the tension, simultaneously therewith smoothing a relatively smaller portion of the skin located in the central portion thereof, and repeating the operations in each of which a larger area in the peripheral portion of the skin is treated simultaneously with a smaller area in the central portion of the skin so that the larger peripheral portions of the skin and the smaller central portion of the skin are completed in the same number of operations. 75
16. In a press for treating kid skins, a pair of presser members movable in straight line reciprocation relatively to each other for engaging opposite sides of a skin to be treated, one of the presser members having a pressure surface of an area considerably smaller than the area of the kid skins to be treated so that edge portions of the kid skin may be held by the hands of the operator on opposite sides of the small-surfaced presser member. 80
17. In a press for treating a class of skins characterized by similarity in size and contour, a pair of presser members movable in straight line reciprocation relatively to each other for engaging opposite sides of a skin to be treated, one of the presser members being of triangular shape with a transverse 90
- 45 median dimension which is considerably less than the diametric dimensions of each skin of the class intended for treatment in the press so that edge portions of each skin may be held by the hands of the operator on each side of the triangularly shaped presser member. 100
- 50 18. In a machine for treating skins through successive operations, a work support, and a triangularly shaped presser member having a portion near the apex of the triangle for applying pressure to a part of the central portion of a skin, and having a broader portion adjacent to or at the base of the triangle adapted to treat a larger part of the 105
- 60 larger peripheral portions of the skin, whereby the larger peripheral portions of the skin are operated upon in the same number of operations required to complete the smaller central portion of the skin. 115
- 65 19. In a machine for treating a class of 120
- skins characterized by similarity in size and contour, triangularly shaped presser members movable relatively to each other to smooth successive portions of a skin, the presser members being considerably smaller as to their pressure applying surfaces than each skin of the class intended for treatment in the press so that edge portions of each skin may be held by the hands of the operator on each side of the triangularly shaped 125
- 70 presser members, and means for causing intermittent operation of the presser members whereby successive portions of both the central and peripheral parts of the skin may be simultaneously treated to complete the treatment of all portions of the skin. 80
- 75 20. That improvement in methods of plating skins which comprises tensioning a skin to efface wrinkles, tucks, or other folded portions, and while maintaining the tension subjecting the skin to a pressing operation. 85
- 80 21. That improvement in methods of plating skins which comprises supporting a portion of a skin on a flat surface and simultaneously therewith tensioning another portion of the skin over a conical surface, and subjecting the flat and the tensioned portions of the skin to pressure to effect plating of the skin. 90
- 85 22. That improvement in methods of plating skins which comprises placing a skin over a flat surface which merges into a conical surface, arranging the skin so that the conical surface points in a direction toward the center of the skin, tensioning a portion of the skin by causing it to conform to the conical surface, and subjecting the flat and the tensioned portions of the skin to pressure and to heat on one surface thereof while the tensioned portion is retained in the conical form, whereby wrinkles, folds or tucks are effaced and the skin is set in a smooth sheet. 100
- 90 In testimony whereof I have signed my name to this specification. 105
